ATTORNEY

UNITED STATES PATENT OFFICE.

OAKLEY SELLECK, OF NEW YORK, N. Y.

DESIGN FOR A DISPLAY-BOX.

SPECIFICATION forming part of Design No. 24,854, dated November 5, 1895.

Application filed September 23, 1895. Serial No. 563,445. Term of patent 3½ years.

To all whom it may concern:

Be it known that I, OAKLEY SELLECK, a citizen of the United States, and a resident of New York, in the county of New York and State of New York, have invented a certain new and useful Design for Display-Boxes for Confectionery or other Articles, of which the following is a specification.

The design consists of the conventionalized representation of the lower portion or calf of a human leg and foot, with a shoe thereon, and trimming at the upper end or terminal of the calf, as represented in the accompany-

ing drawing, which is a side view of the design. 15

In the drawing, A indicates the calf portion, B the foot portion, and C the trimming.

What I claim is—

The design for a display box for confectionery, and similar articles, as shown and described. 20

OAKLEY SELLECK.
